ZIGZAG SEWING MACHINES

Robert A. Hayes, Franklin Park, and George M. Reimer, Elmwood Park, Ill., assignors to Union Special Machine Company, Chicago, Ill., a corporation of Illinois

Application February 3, 1955, Serial No. 485,882

10

16 Claims. (Cl. 112—158)

This invention relates to zigzag sewing machines and particularly to machines of this type which are adapted to provide a seam composed of two-thread stitches of the 404 type through the coaction of a reciprocable needle and a four motion looper, the needle being swung back and forth across the line of feed in the course of forming zigzag stitches.

A primary purpose of the invention has been to provide a machine of the character indicated which is capable of operation at high speeds, i. e. 4500 to 6000 stitches per minute. As heretofore constructed, machines adapted to form stitches of the character indicated have not been capable of operation at speeds over 3000 stitches per minute. Other machines adapted to form zigzag lockstitches of the 304 type have been capable of operation at speeds up to 3500 stitches per minute but the overall productive capacity of these machines is comparatively low due to the necessity of frequently replacing the bobbins in the rotary hooks. The dimensions of a rotary hook are such that a single bobbin can carry only sufficient thread to form a relatively small number of seams and the machine must then be stopped to permit the introduction of a new bobbin. Considerable time is also required for the winding of bobbins. Machines of the character contemplated by the present invention, on the other hand, utilize threads which may be supplied from large cones so that continuous operation over long periods of time is made possible and the necessity of winding bobbins is eliminated.

Factors tending to limit the speed of operation of machines heretofore available for the production of 404 type stitches of the Federal Specifications are the creation of excessive vibration and noise and the causing of excessive wear of various parts when attempts have been made to increase the speed of operation of such machines. The mechanisms employed for producing the desired stitches have been quite complicated and have involved relatively heavy moving parts that have required shifting back and forth to produce the zigzag stitch effect.

In accordance with the present invention a relatively simple and lightweight mechanism is provided for shifting a needle bar carrier back and forth across the line of feed to bring about the production of zigzag stitches. This mechanism involves very few parts which are so mounted and connected as to require a minimum of movement in producing the desired result. Moreover, it is all enclosed within a lubricant tight housing which makes possible the effective lubrication of all wear receiving surfaces.

A special feature of the invention is the provision of an L-shaped lever, of a special, rigid but lightweight construction, which has the junction between its two branches suitably pivoted adjacent the top of the needle head. One leg or branch of this lever extends downwardly within the needle head and carries suitable bearings for the reciprocation of the needle bar therein. The other leg or branch extends substantially horizontally through the hollow overhanging arm of the frame of the

2

machine and terminates within the top of the vertical standard of the frame. Suitable means are provided adjacent the free end of the horizontal leg of the lever to prevent whipping or lateral movement of this end. Simple connections are provided in the vertical standard for imparting rocking movements, of readily variable extent, to the lever. The location of the pivot for the lever, within the needle head, is such as to enable the use of a full length needle bar which extends outwardly from the top of the needle head. It also brings about a desirable relation between the needle and the looper for the formation of stitches for the two lines of reciprocation of the needle bar.

Another special feature of the invention is the provision of a particular form of cam for driving the connections which rock the L-shaped lever discussed above. This cam has only a 70° dwell portion and thus has a more gradual slope to the active portions which bring about the lateral swinging movements of the needle bar. Cams heretofore employed for a similar purpose have been provided with dwells of at least 90°. It has been found that a cam having only a 70° dwell greatly reduces the noise and vibration developed in operating at high speed. A dwell of 90° or more produces particularly objectionable noise and vibration when the lateral movement of the needle bar across the line of feed is relatively great, i. e. around $\frac{3}{16}$ of an inch or greater, and the machine is operated at a speed to provide more than 4000 stitches per minute.

A further special feature of the invention is the provision of an adjustable connection in the linkage connecting the above mentioned cam with the L-shaped lever which is such as to enable infinite adjustment from 0 to a predetermined maximum, say $\frac{1}{4}$ ", of the extent of lateral movement of the needle across the line of feed. Thus the machine may be adapted to produce ordinary two thread stitches of the 401 type or it may be adjusted to produce a stitch of the 404 type having any desired spacing, within the specified limits, between the two lines along which the needle penetrates the work.

Another important feature of the invention is the provision for adequate lubrication of all of the wear receiving parts. This is made possible by the construction and arrangement of the driving connections for the various stitch forming and work feeding instrumentalities and their enclosure within lubricant tight portions of a hollow frame.

Still another feature of the invention is the provision of a top roller feed or puller mechanism and driving connections therefor which are of novel construction and arrangement. An improved, simple expedient is also provided for stripping the work from the surface of the puller roller to prevent wrapping of the work about the roller.

Other objects, features and advantages of the invention will appear from the detailed description of an illustrative embodiment of the same which will now be given in connection with the accompanying drawings, in which:

Fig. 1 is a view, partly in elevation and partly in vertical section, of a sewing machine embodying features of the invention, certain portions of the frame being broken away and various parts being shown in section;

Fig. 2 is an end elevation of the machine, as seen from the left in Fig. 1, the cover plate for the needle head being removed;

Fig. 3 is an end view of the machine, as seen from the right in Fig. 1, portions of the frame being broken away to disclose the interior mechanism;

Fig. 30 is a sectional view through the puller roller of the modified machine; and

Fig. 31 is a front elevational view of the puller roller and related parts.

Referring now to the drawings, the illustrative embodiment of the invention shown in Figs. 1 to 5, inclusive, comprises a frame having a work supporting base portion 10, a vertical standard 11 rising from the right end of the base, and an overhanging arm 12 extending laterally from the upper end of the standard and terminating in a needle head 13. A main drive shaft 14 extends longitudinally of the base and is journaled in suitable bearings provided therein. It projects outwardly from the frame at the right end thereof (Fig. 1) and carries at its outer end a combined handwheel and pulley 15. For convenience in assembling the shaft 14 in the frame, the shaft is divided into several sections which are interconnected by couplings 16 and 17.

Within the needle head there is mounted a vertically reciprocable needle bar 18 carrying at its lower end a

needle 19. The needle bar is mounted in bearings 20 and 21 carried by a vertically disposed rock frame 22 which is pivoted upon a stud 23 carried by the needle head. Stud 23 is positioned adjacent the top of the needle

head and at a point adjacent the path of travel of the needle bar but on that side of the latter which is away from the vertical standard. This arrangement of the stud enables the use of a full length needle bar which extends upwardly through the top of the needle head and may suitably carry a thread take-up arm or eyelet at its upper end. It also causes the needle 19 to assume advantageous positions in relation to the complementary stitch forming means as the frame 22 is rocked about the pivot 23, in the manner to be explained, for the purpose of producing zigzag stitches. Bearing 20 is preferably provided with a plurality of grooves 20a extending circumferentially about the surface of the needle bar.

Similarly, the bearing 21 is preferably provided with a spiral groove 21a in the wall which surrounds the needle bar. These grooves assist in retaining lubricant within the bearings. Secured to the frame 22 is an elongated arm 24 which extends longitudinally through the overhanging arm of the frame. Members 22 and 24 are rigidly interconnected by means of rivets 25 or the like to

form, in effect, an L-shaped lever. At the end of the arm 24 which extends into the hollow vertical standard, adjacent the top of the latter, there is carried a ball-pin 26 having a reduced shank 26a inserted in an opening in the arm 24 and secured therein by means of a set-screw

26. Cooperating with the ball stud 26 is a strap 28 at the upper end of a pitman 29 which has at its lower end another strap 30 cooperating with a ball pin 31 adapted to be secured, in any suitable position of adjustment, along an arcuate slot 32 formed in an upwardly extending portion of a rock member or frame 33 journaled upon a stud 34 within the vertical standard. Pitman 29 is preferably of an extensible character and for this purpose may be formed of a plurality of screw threaded rods 29a and 29b which are coupled by an internally threaded

40 sleeve 29c. The threads at the lower end of rod 29a and at the upper end of rod 29b are of opposite hand so that upon turning of the sleeve 29c the two rods may be either drawn together or urged apart. A nut 29d serves to lock the parts in adjusted position. The rock frame 33 has a forked lower end 35 (Figs. 3 and 9), the two branches of the fork being provided on their inner faces with steel plates 36, formed preferably of clock spring steel, which cooperate with a cam 37 secured to a stub shaft 38. The branches of the forked portion

50 35 of the rock frame are sufficiently resilient to permit the same to be drawn together by means of a bolt 39 to insure a desired close fit in relation to the cam 37. Stud 34 and stub shaft 38 are fixedly mounted in a bracket 40 (Figs. 3, 5, and 11). This bracket has a base 41 secured by screws 42 to a plate 43 fitted over an opening in the front wall of the vertical standard and secured thereto by means of screws 44.

Mounted on a hub extension of the cam 37 and suitably secured to the latter is a gear 45 preferably formed of 60 fibrous material to reduce noise and vibration. Gear 45 meshes with a pinion 46 secured to the shaft 14 within the vertical standard. The gear is of twice as great a diameter as the pinion 46 so that the cam 37 will be given only one revolution for two revolutions of the shaft 14. It will be apparent that as the shaft 14 is rotated the connections described will cause oscillation of the L-shaped frame 22, 24 about the pivot 23 and thus shift the path of the needle 19 successively back and forth in a direction transverse to the line of feed of the work into

70 two alternate positions. As best shown in Fig. 12, the cam 37 is preferably provided with arcuate dwell portions 37a and 37b, each of which extends over an arc of 70°. The intermediate portions 37c and 37d cause the shifting of the L-shaped frame in the manner explained. Heretofore, eccentrics provided in zigzag sew-

ing machines for causing a lateral movement of the needle bar across the line of feed have been provided with 90° dwell portions. It has been found, however, that dwells of 70° are adequate to enable the needle to penetrate the work and pass below the throat plate of the work support and to be retracted to a position above the work. It has been found also that by limiting the dwell portions of the cam to 70°, and thus increasing the extent of the periphery of the cam which is effective in shifting the needle bar frame, there results a substantial reduction in the noise and vibration produced in operating the machine at high speeds. This becomes particularly important when the throw of the needle across the line of feed is relatively great, i. e., $\frac{1}{8}$ of an inch or greater. The eccentricity of the cam 37 may suitably be .092", .125" or .160" for lateral movements of the needle up to $\frac{1}{8}$ ", $\frac{3}{16}$ ", or $\frac{1}{4}$ ", respectively.

It should be understood that the slot 32 (Fig. 3) is arcuate and is curved about the axis of the ball pin 26. Moreover, as shown, the slot 32 extends to a point substantially in vertical alignment with the pivot 34 so that the ball pin 31 may be shifted to such a position. When so shifted no appreciable rocking movement will be imparted to the L-shaped frame 22, 24.

For reciprocating the needle bar 18 the shaft 14 is provided with a crank 47 which is preferably of the form disclosed in the Attwood application, Serial No. 310,295, filed on September 18, 1952. The crank element cooperates with a strap 48 carried by the lower ends of a pair of pitman rods 49 which at their upper ends carry another strap 50 arranged to cooperate with a ball pin 51 extending from the end of a needle lever 52 rockably mounted by means of a shaft 53 extending transversely of the overhanging arm. At its opposite end the needle lever is connected by a link 54 with a clamping element 55 secured to the needle bar 18. Through the connections described the needle bar will be reciprocated upon each revolution of the shaft 14 and the needle 19 will be carried through the work and one or another of two apertures in the throat plate, depending upon the position of the cam 37 in its cycle of operation.

Cooperating with the needle beneath the throat plate is a four-motion looper 56 suitably mounted on the upper end of an arm 57 which is rockable about a pivot stud 58 projecting forwardly from a sleeve 59. This sleeve is secured to a rock shaft 60 suitably journaled in the base of the frame. As best shown in Fig. 8, an arm 61 clamped upon the rock shaft 60 is pivotally connected with the lower end of a strap 62 which cooperates with an eccentric 63 secured to the shaft 14. Suitable needle-avoid movements are imparted to the looper upon the rocking of the shaft 60 through the connections described. Loop-seizing and loop-shedding movements are imparted to the looper by means of a pitman 64 (Figs. 1 and 5) having a strap 65 at one end cooperating with a ball pin 66 extending forwardly from the looper carrier 57. At its opposite end the pitman 64 is provided with a strap 67 which cooperates with a ball pin 68 projecting laterally from an arm 69 secured to a rock shaft 70 mounted in suitable bearings on the frame. The inner or rearward end of the shaft 70 is enlarged, as indicated at 71 in Figs. 5 and 7. A radially extending stud 72 has screw threaded engagement with the enlarged portion 71 of the shaft and carries a ball pin 73 at its outer end cooperating with a strap at the lower end of a pitman 74 whose upper end carries a strap cooperating with a spherical crank element 75 provided on the shaft 14 (Figs. 1 and 7). It will be understood that the timing of the operation of the various stitch forming instrumentalities is so synchronized that upon each revolution of the main shaft 14 a so-called two-thread chain stitch will be produced. Moreover, due to the swinging of the L-shaped frame 22, 24 back and forth across the line of feed upon each two revolutions of the shaft 14 the line

of stitching produced will provide a zigzag effect along the surface of the work.

For advancing work between successive stitches a four-motion feed dog 76 is provided (Figs. 2 and 5). This feed dog is adjustably mounted in a suitable manner at the forward end of a feed bar 77, the rear end of which is rockably mounted, by means of a pivot pin 78, on a feed rocker 79. The latter is carried by a shaft 80 supported by the base portion of the frame. For imparting rocking movements to the feed rocker 79, the latter is provided with a laterally extending stud 80a to which is clamped the rearward end of an arm 81. The forward end of this arm is pivotally connected with a pitman 82 having a strap portion cooperating with an adjustable eccentric 83. Through the connections described work advancing and return movements are imparted to the feed dog. Lifting and lowering movements are imparted to the feed dog in a well known manner by connections from an eccentric 84 (Fig. 1) carried by the shaft 14.

Cooperating with the feed dog in advancing the work is a presser foot 85 which is preferably pivotally mounted upon a shank element 86 clamped upon the lower end of a presser bar 87. This bar is suitably mounted for vertical or axial movement in bearings 88 and 89 carried by the needle head. A spring 90 surrounding the presser bar urges the latter downwardly to retain the presser foot in engagement with the work. To enable the presser bar to be lifted manually or under knee or foot control, there is secured to the bar (Fig. 2) a block 91 which is connected by a link 92 with a lever 93 mounted on a pivot screw 95 within the overhanging arm of the frame. An upwardly extending arm 94 of the lever is connected by a rod 96 with a plate 97 secured to a rock shaft 98 journaled in the rear wall of the vertical standard. Any suitable connections, such as those disclosed in the patent to Peterson, et al., No. 2,598,426, granted May 27, 1952, may be provided for rocking the shaft 98 under control of a knee press or foot treadle or the like. The connections may comprise an arm 99 secured to the shaft 98 (Figs. 2, 3 and 4) and having its free end connected by a chain or rod with a knee press or the like. The arm 99 may also operate a thread tension releasing mechanism. For this purpose a downward extension 99a of the arm may have an elongated camming slot cooperating with a screw stud 100 projecting from an arm 101 clamped upon a rock shaft 102 which extends through the vertical standard from the rear to the front thereof. At its forward end the shaft 102 carries an arm 103 having a pin 104 which acts upon a plate 105, by a camming action or the like, to perform the thread tension releasing function upon the thread tension devices 106 and 107.

Referring now to Fig. 6 there is shown a slightly modified construction which differs from the embodiment of Figs. 1 to 5 inclusive, only in the form and arrangement of the devices for imparting the needle avoid movements to the looper. As shown in Fig. 6, the sleeve 59 upon which the looper carrier is pivotally mounted is secured to a rock shaft 60a which extends into a lubricant retaining chamber 108 provided in the center region of the base of the frame. The devices for rocking the shaft are disposed within this lubricant chamber. They are similar to the devices employed for rocking the shaft 60 as illustrated in Fig. 8. Thus an eccentric 109 similar to eccentric 63 is secured to the shaft 14 and has cooperating therewith a pitman 110, the lower end of which is pivotally connected with an arm 110a secured to the shaft 60a.

In Figs. 13 to 16 inclusive, there is illustrated a modification which embodies a four-motion loop retainer 111. It is desirable to employ such a retainer whenever a relatively wide gauge zigzag stitch is to be produced. This retainer serves to hold the needle thread loop well back on the looper so as to position the thread triangle for proper entry by the needle upon its next descent

through the throat plate. This is particularly desirable when the needle bar carrying frame is in its right hand position (Fig. 1). The mounting and operating connections for the loop retainer 111 are such as to impart to the free end of the retainer an elliptical path such as indicated at 112 in Fig. 15. For this purpose the retainer 111 is retained in an opening 113 in a block 114 secured to the upper surface of a pitman 115 which cooperates with an eccentric 116 secured to the shaft 14. Pitman 115 has a forked extension arranged to cooperate with the rock shaft 60 for sliding movement in relation to the latter. It will be apparent that the eccentric 116 imparts to the retainer the component of its movement which is in the direction of feed. For imparting a component of movement to the retainer in a direction transverse to the line of feed a spherical eccentric 117 is secured to the shaft 14 and cooperates with a strap 118 on a pitman 119. The latter has a strap 120 at its opposite end which cooperates with a ball pin 121 projecting laterally from a sleeve-like member 122 which is oscillatably mounted on a fixed stud or bolt 123. A laterally extending sleeve-like portion 124 of the member 122 is arranged to receive telescopically a pin 125 secured to a strap 126 which cooperates with a ball pin 127 secured to and extending downwardly from the pitman 115. It will be apparent that through the connections described the pitman 115 will be shifted back and forth across the cylindrical surface of the eccentric 116. The two eccentrics 116 and 117 will accordingly impart to the loop retainer the elliptical motion hereinabove mentioned.

When the loop retainer is provided the arrangement disclosed in Fig. 6 for imparting needle avoid movements to the looper should be employed to provide room for the extra eccentrics described above. If desired the eccentric for rocking the shaft 60 may be incorporated in one of the couplings which join the several sections of shaft 14. Thus, as shown in Fig. 13, a combined coupling and eccentric 16a may be provided, this serving to rock the shaft 60 by connections similar to those shown in Fig. 8.

Referring next to Figs. 17 to 21 inclusive, there is illustrated, in detail, the construction of a modified and, in fact, preferred form of L-shaped lever adapted to carry the needle bar and to swing the latter transversely across the line of feed. The modified lever is of lightweight but sturdy construction. It has been found to have less tendency to flex and become distorted, during rapid operations of the machine, than a lever of heavier construction. In this preferred form the lever comprises a pair of L-shaped frames or plates 128 and 129 which are preferably formed of relatively thin sheet steel. These plates or frame pieces are stiffened and united to form a unitary structure by a series of blocks. Thus a block 130 is inserted between the two frame pieces at the lower end of the vertical leg of the lever. This block is preferably formed of ductile cast iron and is copper welded to the two frame pieces. By the employment of ductile cast iron in the production of the block 130, and other of the blocks to be described, various advantages are obtained. In the first place it enables the copper welding of the pieces to form the unitary structure; secondly, ductile cast iron has good bearing and machining qualities.

As best shown in Fig. 20 the block 130 is provided with a centrally disposed bore or passageway extending through the same from top to bottom for the reception of the needle bar. Intermediate its ends the bore is slightly enlarged for clearance purposes in the area designated 132. Adjacent the upper end of the bore there is provided a pair of annular grooves 133 of frusto-conical form for the purpose of retaining lubricant for the needle bar within the bore of the block.

At the elbow of the L-shaped lever there is provided an L-shaped block 134 also preferably formed of ductile cast iron and copper welded to the two side frames 128

and 129. The block 134 is provided with a transversely extending aperture 135 which is aligned with corresponding apertures through the side frames 128 and 129 for the reception of the pivot pin 23 (Fig. 1). This aperture 135 is disposed toward the left side (Fig. 17) of a vertical bore or opening 136 which extends through the block 134. It will be understood that the bore or opening 136 is adapted to receive and provide a bearing surface for the needle bar adjacent the upper end of the latter. The configuration of the bore 136 is preferably as shown and its upper portion is preferably provided with a spiral groove 137 for lubricant retaining purposes.

At several spaced points along the horizontally disposed leg of the lever, reinforcing or stiffening blocks 138 and 139 are provided, these being copper welded to the side frames 128 and 129. At the outer end of the horizontal leg of the lever a block 140 of ductile cast iron is similarly copper welded to the plates 128 and 129. This block is provided with a longitudinally extending opening 141 arranged to receive the shank 26a of the ball pin 26 (Fig. 1). Set screws 142 are provided for retaining the ball pin within the block.

In the use of either of the forms of L-shaped lever disclosed, respectively, in Figs. 1 to 5 inclusive and in Figs. 17 to 21 inclusive, it is desirable to provide guide means adjacent the free end of the horizontally extending arm of the lever. It has been found that in the absence of such guides the long arm of the lever has a tendency to whip laterally as it is oscillated at high speed by the connections described.

As best shown in Figs. 1, 3 and 4, the guide means may suitably comprise a plate 143 disposed horizontally across the top of the lever and secured to suitable lugs on the frame by means of screws 144. These screws cooperate with notches in the ends of the plate and allow for some adjustment of the position of the latter from front to rear of the machine frame. The plate 143 is provided with an outwardly and downwardly projecting extension 145, the vertical portion of which is closely adjacent to the front face of the arm 24 of the lever. An angle member 146 secured by a screw 147 to the top of the projection 145 provides a similar guide surface closely adjacent to the rear face of the arm 24 of the lever. Screw 147 cooperates with an elongated opening through the horizontal leg of the angle member 146 to provide for suitable adjustment. This arrangement permits proper clearance to be provided between the guide surfaces and the outer faces of the arm 24 of the lever to enable free rocking movement of the lever, but the latter is suitably confined and restrained against any lateral whipping action. It will be understood that the downwardly extending arm 22 of the L-shaped lever is suitably confined against lateral movement, both adjacent its lower end and adjacent the pivot stud 23, by cooperating surfaces on the needle head.

In Figs. 22 to 31 inclusive, there is disclosed a machine having the zigzag stitching mechanism described above and having a top feed roller or puller roller arranged to assist in advancing the work. This roller, in the illustrated embodiment, is directly in rear of the path of reciprocation of the needle. If desired, the feed roller may be located more forwardly, i. e. with its axis substantially in the transverse plane of movement of the needle bar and to one side of the path of the needle bar. The machine illustrated in Figs. 22 to 31 inclusive, embodies all of the mechanism provided in the machine illustrated in Figs. 1 to 5 inclusive. It may also embody the modifications described above in relation to other figures. The following description will be confined to the feed roller or puller roller and the mechanism for driving the same.

The feed roller is driven by connections from the gear 46 on the main shaft 14 which, as explained above, serves to drive the mechanism for shifting the needle bar transversely across the line of feed. This gear also meshes with a gear 150, preferably a fibre gear, which in turn meshes with a pinion 151 secured to a shaft 152, jour-

naled in a suitable bearing provided in a housing 153 attached to and projecting rearwardly from the rear face of the base of the frame. As best shown in Figs. 25 and 26, the gear 150 is supported by a screw stud 154 mounted in an opening 155 in an arm 156 having a hub portion 157 turnable within an opening 158 in the housing 153. Gear 150 is retained on the stud 154 by means of a nut 154a having screw threaded engagement with the stud. Similarly, the hub 157, about the axis of which the arm 156 is permitted to turn slightly within the opening 158 of the housing, is retained by means of a nut 157a cooperating with a threaded, reduced portion of the hub 157. The position of the arm 156 and hence the relationship of the gear 150 to the gear 46 and pinion 151 may be adjusted by means of a micrometer screw 159 having screw threaded engagement with an opening 160 in the top of the housing 153. A lock nut 161 serves to retain the micrometer screw in set position. Appropriate adjustment of the arm 156 serves to maintain the gear in proper meshing relation with the gear 46 and pinion 151 so that the train of gearing will rotate freely with a minimum of backlash and chatter. Also the arm 156 may be adjusted to compensate for wear of the gearing.

As best shown in Figs. 22, 23 and 24, the shaft 152 carries a disc or plate 162 forming part of an adjustable eccentric. An eccentric element or crank pin 163 may be shifted to any desired position to provide the eccentricity required for the stitch length desired. Adjustment of the eccentric element 163 may be accomplished by turning of a screw 164, as is well known in the art.

Cooperating with the eccentric element 163 is a strap or collar 165 at the lower end of a pitman 166 which has a strap 167 at its upper end cooperating with a ball pin 168 projecting laterally from an arm 169 extending radially from a plate 169a. The latter is turnably mounted on a shaft 170a suitably supported by the walls of a housing 170 carried by the work supporting surface of the base of the main frame. The plate 169a is arranged to drive a one-way clutch unit carried by the shaft 170a. For this purpose the plate is secured by screws 171 to a spider element 172 arranged for oscillation with the plate about the axis of the shaft 170a. The outer ends of the arms of the spider are curved to conform with the inner surface of a surrounding drum 173. A plurality of rollers 174 which are yieldingly urged in a counterclockwise direction (Fig. 28) by means of springs 175 serve to couple the spider to the drum for rotation of the latter as the plate 169a is turned in a counterclockwise direction, i. e. as the arm 169 is drawn downwardly. As will be understood the arrangement is such that clockwise movement of the spider 172 (Fig. 28) will free the rollers 174 from driving engagement with the drum so that the latter will not be rotated in that direction. A fibre gear 176 having a tight press fit upon a shoulder at the end of the drum 173 is arranged to partake of the movements of the latter. To retain the drum against the clockwise movement mentioned above, there is provided a spider 177, similar to spider 172, having cooperating therewith and with the interior surface of the drum a plurality of rollers 178 spring urged in the same manner as the rollers 174. The spider 177 is secured to a plate or disc 179 by means of screws 180. Plate 179 is mounted upon the shaft 170a but is held against turning with the latter by means of a pin 181 retained within an opening through a wall of the housing 170 and having its inner end in screw threaded engagement with the plate 179. A set screw 181a is provided to retain the pin 181 in the opening through the housing wall. A spring washer 182, which may suitably be of spider form, is interposed between the plate 169a and the adjacent wall of the housing 170 and serves to urge the plate against the outer face of the fibre gear 176. It also urges the opposite end of the drum 173 against the plate 179. A suitable friction force is thus created to prevent overthrow of the drum and gear in their step-by-step movement.

Referring now to Figs. 22 and 24, the fibre gear 176 meshes with a pinion 183 secured to a shaft 184 journaled in the housing 170. The left end of the shaft 184 is connected by a universal coupling 185 with a shaft 186 which, in turn, is connected by a universal coupling 187 with a shaft 188 which, as will be explained, is arranged to drive the feed roller. Preferably the couplings 185 and 187 and the interconnecting shaft 186 are enclosed within a sleeve 189 formed of a suitable flexible material, such as an appropriate plastic. Feed roller 190 is secured to the shaft 188 and arranged to be rotated step-by-step through the connections described. Shaft 188 is journaled in a bearing 191 carried by a bracket 192 having a vertically extending sleeve 193 surrounding and arranged to slide up and down along a pin 194. The latter is fixedly mounted in an opening 194a (Fig. 29) provided an L-shaped bracket 195 suitably clamped upon the lower end of a bearing sleeve 196 surrounding a presser bar 197. To retain the bracket 192 against turning about the pin 194 this bracket is forked, as best shown in Fig. 24, to straddle and cooperate with a flat-sided pin 198 (see also Fig. 23) secured to and extending downwardly from the bracket 195. Another pin 200 (Fig. 22) carried by and extending downwardly from the bracket 195 serves to retain a spring 201, the lower end of which bears against a socket provided in the bearing 191. At its upper end, spring 201 bears against the under face of a washer which is held against axial movement by a nut 201a that is adjustable along a screw-threaded portion 20 of the pin 200 to vary the tension of the spring. As will be seen, the spring 201 serves to urge the feed roller 190 downwardly against the work and the work supporting surface of the base portion of the machine frame. The presser bar 197 is also urged downwardly by a suitable 25 spring, such as the spring 90 of Fig. 2. A block 202 secured to the lower end of the presser bar has a downwardly extending arm 203 at the lower end of which is pivotally mounted a presser foot 204. The arrangement is such that the pressure foot and feed roller have their 30 independent spring means for urging them downwardly against the work so that each may rise and fall independently of the other, as heavier or lighter sections of the work pass beneath them. When the presser bar is lifted under manual, or knee, or foot treadle control by the 35 connections described in relation to Fig. 2, the block 202 is arranged to engage a shoulder which extends over the latter from a member 205 secured to the bearing 191. As shown in Fig. 22, a suitable clearance is provided 40 between the block 202 and the shoulder on member 205 so that the presser foot and presser bar may be lifted in the normal operation of the machine without lifting the feed roller. However, when the presser bar is lifted by the manual means, to facilitate the introduction and 45 removal of work, the feed roller will also be lifted. 50 55 Special means are provided for preventing the work from wrapping around the feed roller. This comprises a bent wire element 207 secured by means of a screw 206 to the element 205. A portion of the wire 207 fits freely within and extends partially around a groove 208 provided in the periphery of the feed roller 190. The free end 209 of the wire 207 extends outwardly and rearwardly away from the feed roller at a suitable angle, approximately 30° to the horizontal. This insures proper stripping of the work from the feed roller and prevents it from clinging to the surface of the roller over any substantial arc. 60 65 It is believed that the operation of the various special features of the devices embodied in the present invention will be clear from the foregoing detailed description of the same so that no resume of operation is required. The machine, however, embodies other features or devices which form no part of the invention to be claimed herein. These include, for example, suitable takeup and control means for the needle thread and the looper thread, certain improved needle thread loop retaining means as- 70 75

sociated with the looper, which is to form the subject matter of a separate application, and the provision of means for automatic lubrication of the major wear receiving surfaces of the mechanism incorporated in the machine. Such lubrication is accomplished by the generation of a lubricant spray within the enclosed portion of the base, the vertical standard, and the overhanging arm, by devices adapted to dip into lubricant retained in the base and at the bottom of the vertical standard. Certain of the mechanism not housed within an enclosed or lubricant tight portion of the frame are lubricated by wicking extending from the reservoir.

As hereinabove explained, the various features and devices incorporated in the new machine are of such character and construction as to enable high speed operation of the machine. When the gauge of the zigzag stitching is relatively narrow the machine may be operated at speeds in excess of 5,000 stitches per minute. For wider gauge zigzag stitching the speed may need to be reduced somewhat but may, in general, be well over 4,000 stitches per minute. Moreover, since the stitch-forming instrumentalities of the machine are in the form of a reciprocating needle and a four-motion looper, adapted to form a 404 type stitch, the stitching threads may be supplied from large cones so that the machine may be operated for long periods of time without changing the thread supply.

While several embodiments of the invention have been disclosed which incorporate certain special features that make possible the operation of a zigzag sewing machine at relatively high speeds, far exceeding those permissible on zigzag machines as heretofore constructed, it should be understood that various changes may be made in the construction and arrangement of the several parts without departing from the general principles and scope of the invention as defined by the appended claims.

What is claimed is:

1. In a sewing machine having a hollow frame comprising a work supporting member, a vertical standard and an overhanging arm carrying a needle head at its end, work feeding means for advancing work across said member, a reciprocable needle bar in said head carrying a needle, a complementary loop taker cooperating with said needle to produce zigzag stitches, and a rotary shaft for driving said work feeding means, said needle bar and said loop-taker, means for carrying said needle bar and for shifting the same across the line of feed which comprises an L-shaped lever rockably mounted on a pivot in said needle head adjacent the top thereof, one leg of said lever extending downwardly in said needle head from said pivot, a plurality of spaced bearings for said needle bar carried by said one leg of the lever, said lever having its other leg extending substantially horizontally through said overhanging arm from a point adjacent said pivot into said vertical standard, and connections in said vertical standard from said shaft to said lever for rocking the latter.

2. In a sewing machine having a hollow frame comprising a work supporting member, a vertical standard and an overhanging arm carrying a needle head at its end, work feeding means for advancing work across said member, a reciprocable needle bar in said head carrying a needle, a complementary loop-taker cooperating with said needle to produce zigzag stitches, and a rotary shaft for driving said work feeding means, said needle bar and said loop-taker, means for carrying said needle bar and for shifting the same across the line of feed which comprises an L-shaped lever rockably mounted on a pivot in said needle head adjacent the top thereof, said pivot being disposed adjacent said needle bar at the side thereof away from said vertical standard, one leg of said lever extending downwardly in said needle head from said pivot, a plurality of spaced bearings for said needle bar carried by said one leg of the lever, said lever having its other leg rigidly connected with said one leg and extend-

ing substantially horizontally through said overhanging arm into said vertical standard, and connections in said vertical standard from said shaft to said lever for rocking the latter.

5. In a sewing machine having a hollow frame comprising a work supporting member, a vertical standard and an overhanging arm carrying a needle head at its end, work feeding means for advancing work across said member, a reciprocable needle bar in said head carrying a needle, a complementary loop-taker cooperating with said needle to produce zigzag stitches, and a rotary shaft for driving said work feeding means, said needle bar and said loop-taker, means for carrying said needle and for shifting the same across the line of feed which comprises an L-shaped lever rockably mounted on a pivot in said needle head adjacent the top thereof, said lever being of lightweight construction and comprising two spaced, substantially parallel sheet-metal members, one leg of said lever extending downwardly in said needle head from said pivot, a plurality of spaced bearings for said needle bar carried by said one leg of the lever between said sheet metal members, said lever having its other leg extending substantially horizontally through said overhanging arm into said vertical standard, and connections in said vertical standard from said shaft to said lever for rocking the latter.

4. In a sewing machine having a hollow frame comprising a work supporting member, a vertical standard and an overhanging arm carrying a needle head at its end, work feeding means for advancing work across said member, a reciprocable needle bar in said head carrying a needle, a complementary loop-taker cooperating with said needle to produce zigzag stitches, and a rotary shaft for driving said work feeding means, said needle bar and said loop-taker, means for carrying said needle bar and for shifting the same across the line of feed which comprises an L-shaped lever rockably mounted on a pivot in said needle head adjacent the top thereof, one leg of said lever extending downwardly in said needle head from said pivot, a plurality of spaced bearings for said needle bar carried by said one leg of the lever, said lever having its other leg extending from a point adjacent said pivot substantially horizontally through said overhanging arm into said vertical standard, stationary guide means carried by said frame adjacent the end of said leg of the lever within said vertical standard, said guide means and said leg having cooperating surfaces arranged to prevent lateral deflection of said leg of the lever, and connections in said vertical standard from said shaft to said lever for rocking the latter.

5. In a sewing machine having a hollow frame comprising a work supporting member, a vertical standard and an overhanging arm carrying a needle head at its end, work feeding means for advancing work across said member, a reciprocable needle bar in said head carrying a needle, a complementary loop-taker cooperating with said needle to produce zigzag stitches, and a rotary shaft for driving said work feeding means, said needle bar and said loop-taker, means for carrying said needle and for shifting the same across the line of feed which comprises an L-shaped lever rockably mounted on a pivot in said needle head adjacent the top thereof, said lever being of lightweight construction and comprising two spaced, substantially parallel sheet-metal members, one leg of said lever extending downwardly in said needle head from said pivot, a plurality of spaced bearings for said needle bar carried by said one leg of the lever between said sheet metal members, said bearings being formed of ductile cast iron and being copper welded to said sheet metal members, said lever having its other leg extending substantially horizontally through said overhanging arm into said vertical standard, and connections in said vertical standard from said shaft to said lever for rocking the latter.

6. In a sewing machine having a hollow frame comprising a work supporting member, a vertical standard and an overhanging arm carrying a needle head at its end, work feeding means for advancing work across said member, a reciprocable needle bar in said head carrying a needle, a complementary loop-taker cooperating with said needle to produce zigzag stitches, and a rotary shaft for driving said work feeding means, said needle bar and said loop-taker, means for carrying said needle and for shifting the same across the line of feed which comprises an L-shaped lever rockably mounted on a pivot in said needle head adjacent the top thereof, said lever being of lightweight construction and comprising two spaced, substantially parallel sheet-metal members, one leg of said lever extending downwardly in said needle head from said pivot, a plurality of spaced bearings for said needle bar carried by said one leg of the lever between said sheet metal members, said bearings being formed of ductile cast iron and being copper welded to said sheet metal members, each of said bearings having lubricant retaining grooves extending around the inner bearing surface thereof, said lever having its other leg extending substantially horizontally through said overhanging arm into said vertical standard, and connections in said vertical standard from said shaft to said lever for rocking the latter.

7. In a sewing machine having a hollow frame comprising a work supporting member, a vertical standard and an overhanging arm carrying a needle head at its end, work feeding means for advancing work across said member, a reciprocable needle bar in said head carrying a needle, a complementary loop-taker cooperating with said needle to produce zigzag stitches, and a rotary shaft for driving said work feeding means, said needle bar and said loop-taker, means for carrying said needle bar and for shifting the same across the line of feed which comprises a rigid L-shaped lever rockably mounted on a pivot in said needle head adjacent the top thereof, one leg of said lever extending downwardly in said needle head from said pivot, a plurality of spaced bearings for said needle bar carried by said one leg of the lever, said lever having its other leg extending substantially horizontally through said overhanging arm into said vertical standard, and connections in said vertical standard from said shaft to said lever for rocking the latter, said connections comprising a stub shaft journaled in said vertical standard, connections from said rotary shaft for rotating said stub shaft at half the angular speed of said rotary shaft, a cam secured to said stub shaft and having opposed dwell portions each extending over an arc of not more than about 70° , the intermediate portions of said cam having gradually sloping camming surfaces, a rock member mounted in said vertical standard arranged to be rocked by said cam, and connections from said rock member to said lever.

8. In a sewing machine having a hollow frame comprising a work supporting member, a vertical standard and an overhanging arm carrying a needle head at its end, work feeding means for advancing work across said member, a reciprocable needle bar in said head carrying a needle, a complementary loop-taker cooperating with said needle to produce zigzag stitches, and a rotary shaft for driving said work feeding means, said needle bar and said loop-taker, means for carrying said needle bar and for shifting the same across the line of feed which comprises a rigid L-shaped lever rockably mounted on a pivot in said needle head adjacent the top thereof, one leg of said lever extending downwardly in said needle head from said pivot, a plurality of spaced bearings for said needle bar carried by said one leg of the lever, said lever having its other leg extending substantially horizontally through said overhanging arm into said vertical standard, and connections in said vertical standard from said shaft to said lever for rocking the latter, said connections comprising a cam driven from said rotary shaft at half the angular speed of

the latter, a rock member mounted for rocking movement about a pivotal axis in said vertical standard and cooperating with said cam for rocking movement thereby, and a link pivotally connected at one end with said rock member and at its other end with said lever, the point of pivotal connection with said rock member being adjustable to vary the extent of movement of the lever, the arrangement being such that in one position of adjustment of said point of pivotal connection no appreciable movement is imparted to said lever.

9. In a sewing machine having a hollow frame comprising a work supporting member, a vertical standard and an overhanging arm carrying a needle head at its end, work feeding means for advancing work across said member, a reciprocable needle bar in said head carrying a needle, a complementary loop-taker cooperating with said needle to produce zigzag stitches, and a rotary shaft for driving said work feeding means, said needle bar and said loop-taker, means for carrying said needle bar and for shifting the same across the line of feed which comprises a rigid L-shaped lever rockably mounted on a pivot in said needle head adjacent the top thereof, one leg of said lever extending downwardly in said needle head from said pivot, a plurality of spaced bearings for said needle bar carried by said one leg of the lever, said lever having its other leg extending substantially horizontally through said overhanging arm into said vertical standard, and connections in said vertical standard from said shaft to said lever for rocking the latter, said connections comprising a cam driven from said rotary shaft at half the angular speed of the latter, a rock member mounted for rocking movement about a pivotal axis in said vertical standard and cooperating with said cam for rocking movement thereby, and a link pivotally connected at one end with said rock member and at its other end with said lever, said link being substantially vertically disposed in said standard and having the pivot at its lower end adjustable along a substantially horizontal slot in said rock member, said slot extending to a point substantially directly above the axis about which said rock member is rocked.

10. In a sewing machine having a hollow frame comprising a work supporting member, a vertical standard and an overhanging arm carrying a needle head at its end, work feeding means for advancing work across said member, a reciprocable needle bar in said head carrying a needle, a complementary loop-taker cooperating with said needle to produce zigzag stitches, said loop-taker comprising a four motion looper pivotally mounted for oscillation in a direction across the line of feed and mounted for rocking movement along the line of feed, and a rotary shaft for driving said work feeding means, said needle bar and said loop-taker, means for carrying said needle bar and for shifting the same across the line of feed which comprises an L-shaped lever rockably mounted on a pivot in said needle head adjacent the top thereof, one leg of said lever extending downwardly in said needle head from said pivot, a plurality of spaced bearings for said needle bar carried by said one leg of the lever, said lever having its other leg extending substantially horizontally from a point adjacent said pivot through said overhanging arm into said vertical standard, and connections in said vertical standard from said shaft to said lever for rocking the latter.

11. A sewing machine having a hollow frame comprising a work supporting member, a vertical standard and an overhanging arm carrying a needle head at its end, work feeding means for advancing work across said member, a reciprocable needle bar in said head carrying a needle, a complementary loop-taker cooperating with said needle to produce zigzag stitches, said loop-taker comprising a four motion looper pivotally mounted for oscillation in a direction across the line of feed and mounted for rocking movement along the line of feed, a four motion loop retainer having a needle thread loop retaining end arranged

for elliptical movement in a substantially horizontal plane in a region above and adjacent said looper, means for imparting an elliptical motion to said loop retainer, a rotary shaft for driving said work feeding means, said needle bar, said loop-taker, and said loop retainer, means for carrying said needle bar and for shifting the same across the line of feed which comprises an L-shaped lever rockably mounted on a pivot in said needle head adjacent the top thereof, one leg of said lever extending downwardly in said needle head from said pivot, a plurality of spaced bearings for said needle bar carried by said one leg of the lever, said lever having its other leg extending substantially horizontally from a point adjacent said pivot through said overhanging arm into said vertical standard, and connections in said vertical standard from said shaft to said lever for rocking the latter.

12. A zigzag sewing machine having a hollow frame with a work supporting base, a vertical standard, and an overhanging arm carrying a needle head at its end, said needle head, overhanging arm, and vertical standard together with a portion of said base forming a lubricant tight housing, means for creating a lubricant mist within said housing, a four-motion feed dog within said base for advancing work across the work supporting surface thereof, a reciprocable needle bar in said needle head carrying a needle at its lower end, a complementary loop-taker in said base cooperating with said needle to produce zigzag stitches, a rotary drive shaft extending longitudinally of said base, connections from said shaft for driving said work feeding means, said needle bar, and said loop-taker, at least a portion of said connections for driving said needle bar and loop-taker being disposed within said lubricant tight housing, means for carrying said needle bar and for shifting the same across the line of feed, said means comprising a rigid L-shaped lever rockably mounted on a pivot in said needle head adjacent the top thereof, said lever being enclosed within said lubricant tight housing, and connections within said housing from said shaft to said lever for rocking the latter back and forth upon each two revolutions of said shaft.

13. A zigzag sewing machine having a hollow frame with a work supporting base, a vertical standard, and an overhanging arm carrying a needle at its end, said needle head, overhanging arm, and vertical standard together with a portion of said base forming a lubricant tight housing, means for creating a lubricant mist within said housing, a four-motion feed dog within said base for advancing work across the work supporting surface thereof, a reciprocable needle bar in said needle head carrying a needle at its lower end, a four-motion looper in said base cooperating with said needle to produce zigzag stitches, a rotary drive shaft extending longitudinally of said base, connections from said shaft for driving said work feeding means, said needle bar, and said looper, said connections for driving said needle bar and looper including eccentric elements on said shaft disposed within said lubricant tight housing, means for carrying said needle bar and for shifting the same across the line of feed, said means comprising a rigid L-shaped lever rockably mounted on a pivot in said needle head adjacent the top thereof, said lever being enclosed within said lubricant tight housing, and connections within said housing from said shaft to said lever for rocking the latter back and forth upon each two revolutions of said shaft.

14. A zigzag sewing machine having a hollow frame with a work supporting base, a vertical standard, and an overhanging arm carrying a needle head at its end, said needle head, overhanging arm, and vertical standard together with a portion of said base forming a lubricant tight housing, means for creating a lubricant mist within said housing, a four-motion feed dog within said base

for advancing work across the work supporting surface thereof, a feed roller above said work supporting base cooperating with the work to assist in advancing the same, a reciprocable needle bar in said needle head carrying a needle at its lower end, a complementary loop-taker in said base cooperating with said needle to produce zigzag stitches, a rotary drive shaft extending longitudinally of said base, connections from said shaft for driving said work feeding means, said feed roller, said needle bar, and said loop-taker, at least a portion of said connections for driving said feed roller, said needle bar and said loop-taker being disposed within said lubricant tight housing, means for carrying said needle bar and for shifting the same across the line of feed, said means comprising a rigid L-shaped lever rockably mounted on a pivot in said needle head adjacent the top thereof, said lever being enclosed within said lubricant tight housing, and connections within said housing from said shaft to said lever for rocking the latter back and forth upon each two revolutions of said shaft.

15. A zigzag sewing machine having a hollow frame with a work supporting base, a vertical standard, and an overhanging arm carrying a needle head at its end, a four-motion feed dog within said base for advancing work across the work supporting surface thereof, a feed roller above said work supporting base cooperating with the work to assist in advancing the same, a reciprocable needle bar in said needle head carrying a needle at its lower end, a complementary loop-taker in said base cooperating with said needle to produce zigzag stitches, a rotary shaft extending longitudinally of said base, connections from said shaft for driving said work feeding means, said feed roller, said needle bar, and said loop-taker, means for carrying said needle bar and for shifting the same across the line of feed, said means comprising a rigid L-shaped lever rockably mounted on a pivot in said needle head adjacent the top thereof, said lever being enclosed within said needle head and overhanging arm, and connections within said vertical standard from said shaft to said lever for rocking the latter back and forth upon each two revolutions of said shaft.

16. A zigzag sewing machine having a hollow frame with a work supporting base, a vertical standard, and an overhanging arm carrying a needle head at its end, a four-motion feed dog within said base for advancing work across the work supporting surface thereof, a feed roller above said work supporting base cooperating with the work to assist in advancing the same, a reciprocable needle bar in said needle head carrying a needle at its lower end, a complementary loop-taker in said base cooperating with said needle to produce zigzag stitches, a rotary shaft extending longitudinally of said base, connections from said shaft for driving said work feeding means, said feed roller, said needle bar, and said loop-taker, means for carrying said needle bar and for shifting the same across the line of feed, said means comprising a rigid L-shaped lever rockably mounted on a pivot in said needle head adjacent the top thereof, said lever being enclosed within said lubricant tight housing, and connections within said housing from said shaft to said lever for rocking the latter back and forth upon each two revolutions of said shaft, said last mentioned connections including a pinion on said shaft which also forms a part of the connections for driving said feed roller.
